UNITED STATES PATENT OFFICE.

WILLIAM JAMES HADDEN, OF GLASGOW, SCOTLAND, ASSIGNOR TO DONALDSON MANUFACTURING COMPANY LIMITED, OF GLASGOW, SCOTLAND.

GOLF CLUB.

Application filed May 12, 1927, Serial No. 190,740, and in Great Britain August 16, 1926.

This invention relates to golf clubs and refers to that class of such in which the parts, namely the shaft (preferably of hollow steel), the head and the grip are made as separate, self-existent units which are secured together mechanically, by means involving a clamping action, to form the complete club.

The object of the present invention is to provide an improved and practical construction of such golf clubs, all the parts of which are so secured together that, while they retain the advantages of such clubs in being capable of having the constituent unit parts made and stored separately and being capable of assembly at any time to suit the desire of the dealer or the user, the parts will be immovable relatively to each other in use, and, moreover, the golf club so made will simulate a golf club of the usual form having a hickory shaft, a wooden or iron head and a wrapped grip.

By making all the constituent parts as separate, self-existent units which can be readily assembled only a few completely finished clubs need be kept in stock, say, one or more as samples of each kind of club. There would be a range of heads for drivers, for bassies, for irons, etc., likewise a range of shafts for each character of club and also a range of grips varying in thickness suitable for the user and these would be finished and complete in themselves and made so that they could be readily fitted together by unskilled labour to form the complete club.

According to this invention the golf club comprises, in combination, a shaft, a grip adjustable on one end of said shaft, means for clamping said grip on the shaft; a head with socket adapted to fit on the other end of said shaft and circumferentially contractible means for clamping said socket on the shaft.

The head may be made with a contractible socket adapted to fit snugly on the end of the shaft and have means (such as a screw plug) for detachably securing it to the shaft and means for contracting said socket so as to clamp it on said shaft.

The heads are made by machinery or otherwise to certain standard patterns, the shafts are made to certain standard lengths and the grips are made to certain standard thicknesses. At the factory, sets of each

pattern of head, shaft, and grip would be kept and would always be available ready for assembly.

The dealer or user would take a tubular steel shaft of suitable length, then a finished head of suitable shape, weight, and lie, and affix it to the shaft and then a suitable complete grip and mount and adjust it on the shaft selected, so that a completely finished club would be formed, built up specifically to suit the user, who, if at hand, can test the club thus formed and, if necessary, change one or more of its component parts for another part or other parts.

In the drawing,

Fig. 1 is a longitudinal sectional view of a golf club with an iron head.

Fig. 2 is a sectional view on line II—II in Fig. 1.

Fig. 3 is an enlarged sectional view on line III—III in Fig. 1.

Fig. 4 is an enlarged sectional view on line IV—IV in Fig. 1.

In the assembled club shown in the drawing the iron head is marked 1, the hollow steel shaft 2 and the grip 3.

The iron head is secured to the steel shaft by making the end of the socket 4 of the head of reduced thickness, this end being tempered and slotted longitudinally at 5 and 85 having its exterior surface provided with a tapered thread 6. Moreover the head is internally threaded at 7. The lower end of the shaft is arranged to fit snugly into the socket which is tapered to correspond to the 90 shaft and this end is provided with a plug 10 secured to the shaft for instance by rivets 11 said plug having a tapped extension 12 adapted to screw into the threaded part 7 so that the head selected could be readily 95 attached to the shaft selected by screwing the shaft into the socket, the extension 12 acting to draw the shaft so as to cause it to fit snugly in the socket. An internally threaded ferrule 13 is then tightened over 100 the slotted end of the socket to cause it to firmly grip the shaft and clamp the head thereto. The ferrule has a curved upper end 14 which fits with clearance around the shaft and the external surface of the ferrule 105 is knurled.

In cases where it is not convenient to temper the socket of the head, the socket may have tightly fitted therein a tubular part, suitably split, for the reception of the 110

steel shaft. A clamping ferrule would then be fitted on the tube.

In the case of wooden heads, a short length of tubing or a hollow collar may be provided on the neck to form the socket for the reception of the steel shaft. The collar or tube would be screwed internally and a clamping ferrule provided as for iron heads.

For ordinary clubs, i. e. for clubs for right handed players, the screw threads on the shaft and in the socket are left handed so that at every stroke there is a tendency to tighten up the screw engagement. Right hand screw threads are desirable for left handed players.

The grip for completing the club comprises a hollow metal sleeve 20, covered with leather 21 or other material, the said sleeve being capable of slidably fitting on the end 20 of the club shaft. Preferably a wedge-shape piece 30 is provided between the sleeve 20 and the covering 21 to form a bulge at the upper end of the club.

The usual leather or fabric strip 21 for the hands is wound upon the grip and secured in the customary way. At the end to be located nearer the head, the sleeve is split by four longitudinal slits 22 and, when in position on the shaft, a ferrule 23 having a conical internally screw-threaded portion is slipped over the slits and screwed up on a left hand thread on the sleeve, thus reducing the circumference of the sleeve and clamping it tightly to the shaft. If desired, there may be an additional short sleeve (not shown) which is clamped to the shaft and the main sleeve may be fitted thereon or thereover and clamped in its turn, a double clamping being thus obtained.

40 The end of the shaft is closed by a plug 24 adapted to be fixed in the shaft by the grub screw 31 having an axial screw threaded hole 25 in it. The upper end of the sleeve is also closed by a milled head 26 on a long screw 27 which screws into the plug of the shaft so as to hold the grip truly in position.

It is obvious that by turning the milled head 26 of the screw 27 the sleeve can be 50 nicely adjusted in position and, after being clamped, the screw can be tightened positively to prevent any longitudinal movement of the sleeve on the shaft.

To prevent positively any turning of the grip on the shaft, the shaft is provided with 55 one or more longitudinal external grooves

or channels as 28 and the sleeve has corresponding internal ribs or projections 29 so that when sliding the grip on to the shaft the rib or ribs is or are engaged with the 60 groove or grooves. Alternatively the rib or ribs may be on the shaft and the groove or grooves in the sleeve. The simplest way is as shown to make the longitudinal depressions or channels externally on both the 65 sleeve and the shaft, the external longitudinal depressions in the thin sleeve forming internal ribs adapted to engage and slide in the channels of the shaft.

The grip, when fitted, is secured to the 70 shaft at both its ends in a way which allows it to be readily loosened if not exactly suited to the desire of the player, and moved along the shaft within limits, or replaced by a different and more suitable grip which 75 can be similarly attached to the shaft, so that the trouble of loosening the binding strip, altering the length of the shaft by cutting it and replacing the binding is obviated.

It will be appreciated that the foregoing manner of manufacturing golf clubs is a great improvement over the existing manner. A model exactly as desired by each 85 player can be readily built up from standardized parts. Then again there is a considerable saving in packing and transport as a number of shafts can be packed together into small bulk and likewise a number of grips and a number of heads.

I claim:—

1. A golf club comprising, a shaft, a club head having a contractible socket adapted to fit snugly on one end of said shaft, a screwed plug on said shaft adapted to screw 95 into the said head, means for contracting said socket so as to clamp it on the shaft, and a grip detachably fixed on the other end of said shaft.

2. A golf club comprising, a hollow steel 100 shaft, a club head with a socket adapted to fit snugly on one end of said shaft, said socket having a tapered end of reduced thickness, which is slotted longitudinally so that it is contractible, a screwed plug on 105 said shaft adapted to screw into said head, an internally threaded ferrule adapted to screw on to the end of said socket to clamp the head to the shaft, and a grip detachably fixed on the other end of said shaft.

In testimony whereof I affix my signature.

WILLIAM JAMES HADDEN.
